CLAIM

The ornamental design for a vehicle windshield, as shown and described.

DESCRIPTION

FIG. 1 is a top-down plan view of a vehicle windshield showing our new design;

FIG. 2 is a bottom-up plan view of thereof;

FIG. 3 is a front elevational view of the vehicle windshield;

FIG. 4 is a left side elevational view of the vehicle windshield showing an outline wire frame of a vehicle, the right side being a mirror image thereof;

FIG. 5 is section view of the vehicle windshield taken along the lines 5—5 of FIG. 3;

FIG. 6 is a top edge view thereof;

FIG. 7 is a bottom edge view thereof;

FIG. 8 is an alternative bottom-up plan view of the vehicle windshield showing a ceramic paint applied to a portion of the inner surface thereof;

FIG. 9 is an alternative front elevation view of the vehicle windshield showing a ceramic paint applied to a portion of the inner (bottom) surface thereof; and,

FIG. 10 is an alternative left side elevational view showing an outline wire frame of a vehicle, the right side view being a mirror image thereof.

The broken lines shown in the drawings are for illustrative purposes only and form no part of the claimed design.
